UNITED STATES PATENT OFFICE.

ALBERT COWELL, OF KIDDERMINSTER, ENGLAND.

DESIGN FOR A CARPET-PATTERN.

Specification forming part of Design No. 5,886, dated June 4, 1872.

To all whom it may concern:

Be it known that I, ALBERT COWELL, of Kidderminster, Worcestershire, in England, have invented a new and original Design for Carpets; and I do hereby declare that the following is a full, clear, and exact description thereof, which will enable others skilled in the art to make and use the same, reference being had to the accompanying photographic illustration forming part of the specification.

The nature of my invention is fully represented in the accompanying photographic illustration, to which reference is made.

This invention relates to a new floral design to serve as ornamentation on carpets or other fabrics. The design consists of a bouquet of roses and other flowers interspersed with leaves. The bouquet is shown to be supported on a double-scroll, from which flowers and vines are also suspended.

I claim as my invention—

The design for carpets, as shown.

ALBERT COWELL.
